UNITED STATES PATENT OFFICE.

JOHN D. HENDRIX, OF SEATTLE, WASHINGTON, ASSIGNOR TO OLIVER Z. PERRY, OF LOS ANGELES, CALIFORNIA.

DESIGN FOR A CASING FOR A DIRECTION SIGNAL LAMP.

Application filed April 17, 1924. Serial No. 9,312. Term of patent 3½ years.

To all whom it may concern:

Be it known that I, JOHN D. HENDRIX, a citizen of the United States of America, residing at Seattle, in the county of King and State of Washington, have invented a new, original, and ornamental Design for Casing for Direction Signal Lamp, of which the following is a specification, reference being had to the accompanying drawing, forming part thereof.

Fig. 1 is a front elevational view of a casing for a direction signal.

Fig. 2 is a side view of the same.

I claim:—

The ornamental design for a casing for a direction signal lamp, as shown.

JOHN D. HENDRIX.
